 LLP(57) **CLAIM**

The ornamental design for a toy storage bin, as shown, and described.

DESCRIPTION

FIG. 1 is a perspective view of a toy storage bin;

FIG. 2 is a front view thereof;

FIG. 3 is a rear view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a perspective view thereof in a use environment.
 The broken lines represent unclaimed matter and form no
 part of the claimed design.**1 Claim, 8 Drawing Sheets**FIG. 1

FIG. 2

FIG. 3

FIG. 4

FIG. 5

FIG. 6

FIG. 7

FIG. 8
